[57] CLAIM

The ornamental design for a kneeling frame or similar article, as shown and described.

DESCRIPTION

FIG. 1 is a perspective view of a kneeling frame or similar article showing my new design;

FIG. 2 is a side view of the inventive kneeling frame;

and

FIG. 3 is a front view of the inventive kneeling frame. The opposite side view of the kneeling frame is substantially identical to the side view of FIG. 2 and the bottom is substantially flat and unadorned.

FIG. 1.

FIG. 2.

FIG. 3.
